DESIGN FOR AN AUTOMOBILE SEAT

Charles E. McCormick, Detroit, Mich.

Application July 25, 1946, Serial No. 131,916

Term of patent 14 years

(Cl. D14—6)

To all whom it may concern:

Be it known that I, Charles E. McCormick, a citizen of the United States of America and residing at Detroit, county of Wayne, State of Michigan, have invented a new, original, and ornamental Design for an Automobile Seat, of which the following is a specification, reference being made to the accompanying drawings, forming a part thereof.

Fig. 1 is a perspective view of the back and one side of a seat, showing my design, and

Fig. 2 is a perspective view of the front and side of the seat, the other side, not shown, is substantially like the side shown.

The broken line representation of an automobile body is shown purely for illustrative purposes.

I claim:

The ornamental design for an automobile seat, substantially as shown and described.

CHARLES E. McCORMICK.
